UNITED STATES PATENT OFFICE.

PAUL J. RAY, OF LAKEWOOD, OHIO.

COMPRESSION-RHEOSTAT.

1,092,952.

Specification of Letters Patent. Patented Apr. 14, 1914.

Application filed June 21, 1913. Serial No. 775,158.

To all whom it may concern:

Be it known that I, PAUL J. RAY, a citizen of the United States, residing at Lakewood, in the county of Cuyahoga and State 5 of Ohio, have invented a new and useful Compression-Rheostat, of which the following is a specification.

The present invention relates to improvements in compression rheostats, in which the 10 resistance medium, whose electrical conductivity is increased when it is subjected to pressure, is so mounted, that the production of air gaps between the members thereof, is prevented when the rheostat is in normal 15 non-compressed position, there being provided manually controlled means for compressing the resistance medium, so that the resistance thereof is decreased as the rheostat is operated to permit the flow of current 20 to the motor or other means to which the current is directed.

A further object of the present invention, is the provision of a switch board rheostat, of the compression type, which is disposed 25 to vary the compression on the disks, which are made of carbon or of any other material that will act similarly, such disks being mounted in an insulated tube so that the operating lever of the rheostat, may be 30 moved from the minimum to the maximum compression of the disks from an extreme position at one side to an extreme position upon the other side.

With the foregoing and other objects in 35 view which will appear as the description proceeds, the invention resides in the combination and arrangement of parts and in the details of construction hereinafter described and claimed, it being understood that 40 changes in the precise embodiment of the invention herein disclosed can be made within the scope of what is claimed without departing from the spirit of the invention.

In the drawings—Figure 1 is a view 45 partly in side elevation and partly in section of a switch board type of rheostat. Fig. 2 is a front elevation of the controlling means thereof. Fig. 3 is an enlarged sectional view through the outer end of the resistance medium tube, and the rod for the 50 compression unit thereof. Fig. 4 is an enlarged detail sectional view of the means interposed between the cam and the resistance medium compression rod. Fig. 5 is a 55 side elevation of a floor type rheostat. Fig.

6 is an enlarged detail sectional view of the cross head operated by the cam and carried by the means as shown in Fig. 4 acting upon a plurality of compression rods.

Referring to the drawings, the numeral 1 60 designates a frame, provided with the clamping device 2 for the reception of the tube 5, which is insulated therefrom by the insulating sleeve 3 mounted in the insulating plug 4 disposed within the frame, as clearly 65 shown in Figs. 1, 3 and 5.

Carried by the sleeve 3, is a tube 5 of insulation or coated internally with insulation, the same having disposed therein, a plurality of disks 6, which are preferably of carbon, 70 or may be of any material that will operate, so that the conductivity thereof is increased due to the compression of the same. A slideable rod 7 is mounted in the outer open end of the tube 5, and carries the actuating button 8, to which is connected the flexible leaf terminal conductor 9, which constitutes one terminal of an electrical circuit. The opposite end of the tube 5 has disposed therein, a metal stud 10 insulated from the tube 5 by 80 means of a mica washer 31, provided with the binding screws 11 for another terminal connection so that the resistance medium consisting of the disks 6 will be interposed between the conductors led to the plate 9 and 85 from the binding post or stud 10.

As shown in Fig. 1, the rheostat is properly connected to a switch board 12, by means of the bolts or screws 13, which maintain the plate 14 in the proper relation to 90 the frame 1, the two projecting apertured lugs 15 and 16 of the frame or plate 14, constituting a support for the operating cam 18, which is pivoted upon the pivoting bolt 17 and provided with the operating handle 19. 95 A graduated scale S is carried by the projection 16, and co-operates with the pointer B of the lever 19, so that the operator may know at a glance the relative position of the compression units 6 when the handle 19 is 100 manipulated.

In order to interpose a resilient connecting medium between the operating button 8 of the compression units, and the cam 18, an aperture 20 is formed in the plate 14, and 105 has slidably mounted therein a cylindrical socketed member 21, carrying in its outer end the anti-frictional roller 22 which is normally held resiliently against the cam 18. The socket 23 of the member 21 has mounted 110

therein, a rod 24, whose head 25, as shown in Fig. 1 is disposed to engage the button 8 and be held in resilient contact therewith by means of the light spring 26 mounted with-
 5 in the socket 23, as clearly illustrated in Fig. 4. This spring is of such tension, as to nor-
 mally hold the head 25 projected without any strain being placed upon the heavier
 10 spring 27, which when the lever 19 is op-
 erated to cause the cam to move the member
 21 toward the resistance medium, will re-
 ceive the main force of such cam action, so
 that the head 25 will compress the disks 6 to
 increase the conductivity thereof.
 15 It will thus be seen that when the lever 19
 is in zero position, that the strain upon the
 spring 27 will be removed, that the light re-
 sistance of the spring 26, will hold the stud
 20 projected so that the disks 5 of the re-
 sistance medium will be held in contact suffi-
 ciently to prevent any air spaces or gaps
 25 therebetween. This feature is of the utmost
 importance, as it prevents any undue separa-
 tion of the disks, and any tendency to spark
 or burn during the initial introduction of
 the current therethrough when the lever 19
 is operated.
 As shown in Figs. 5 and 6, a floor type
 30 rheostat is provided, and although a single
 resistance medium 5 is shown in Fig. 1, it is
 evident that a plurality of the same may be
 provided according to the use to which the
 35 same is to be placed. In the floor type, two
 resistances 6' are shown, the same being
 properly mounted in the clamp members 2'
 carried by the frame supporting base 1'. In
 the floor type rheostat, the contact terminals
 40 9', which are insulated from the clamp 2',
 are respectively connected to the slidable
 rods (not shown), by means of the flexible
 leaf terminal conductors 9'', which provide
 means for connecting the rheostat in an elec-
 45 trical circuit. The insulating button 8' of
 the two slidable rods (not shown) are pro-
 jected to be engaged by the respective ex-
 treme ends of a cross bar 25', said bar 25'
 being pivoted to the stud 24', which corre-
 50 sponds to the stud 24 of the device, as shown
 in Fig. 4, by means of the screw 32. A rod
 29 is slidably mounted in the projection 30
 of the cross bar 25' and is fixed to the frame
 14', or this construction may be reversed,
 and rod 29 may be slidably mounted in the
 55 frame 14' and threaded through the projec-
 tion 30. The cross bar 25' is permitted a
 straight line movement due to the actuation
 of the lever 19' and its cam 18', which bears
 upon the roller 22' of the member 21', all of
 60 which is similar to the device, as shown in
 Figs. 1 and 2. In this structure, the two
 resistance mediums are connected by the
 cross connection 11', to the binding posts 11',
 and have the insulating washers 31' all as
 65 clearly illustrated in Fig. 5. By this ar-
 rangement the resistance mediums are con-

nected in a series, but, however, the resist-
 ance mediums may be connected in parallel
 when a low minimum resistance is desired.

What is claimed is:

1. A compression rheostat, including a 70
 resistance medium, the conductivity of
 which is increased due to pressure exerted
 thereupon, a pivoted lever provided with a
 cam, and means interposed between the cam
 75 of the pivoted lever and the resistance me-
 dium whereby under normal conditions, the
 resistance medium is held with the members
 thereof in contact to prevent air gaps, and
 whereby when the handle is operated, the re-
 sistance medium is compressed. 80

2. A rheostat, including a frame, a clamp
 carried thereby, an internally insulated tube
 mounted in the clamp, a plurality of con-
 ductor disks mounted in said tube, a cam
 pivotally mounted in the frame, and a resili-
 ent plunger connection between the cam and
 85 the disks, whereby the disks are normally
 held against separation to prevent the for-
 mation of air gaps when the cam is in nor-
 mal position and the disks are compressed
 90 when the cam is operated.

3. A rheostat, including a frame, a clamp
 carried thereby, an internally insulated tube
 mounted in the clamp, a plurality of con-
 ductor disks mounted in said tube, a cam pivot-
 95 ally mounted in the frame, a resilient plun-
 ger connection between the cam and the
 disks, whereby the disks are normally held
 against separation when the cam is in nor-
 mal position and the disks are compressed 100
 when the cam is operated, said resilient
 connection comprising a cylindrical socket,
 a stud slidably mounted in said socket, and
 two springs of varying tension interposed
 105 in the socket between the ends of the stud,
 the lighter spring normally holding the stud
 in engagement with the disks to hold the
 disks against separation.

4. A rheostat, including a frame, a tube
 of insulation mounted in the frame, a plu-
 rality of conductor disks mounted in said
 tube, a lever pivoted in the frame, a cam
 carried thereby, and a two membered plun-
 ger mounted slidably in the frame and inter-
 110 posed between the cam and the disks, said
 members being resiliently separated and
 forming a resilient compression transmission
 agent between the cam and the disks. 115

5. A rheostat, including a frame, a sleeve
 carried thereby, an internally insulated tube
 mounted in the sleeve, a plurality of con-
 ductor disks mounted in said tube, a slidably
 mounted rod for engaging the disks and pro-
 jecting exteriorly of the sleeve, a handle piv-
 120 otally connected to the frame, a cam carried
 by said handle, a slidably mounted two
 part plunger carried by the frame and in-
 terposed between the cam and the rod,
 whereby the manipulation of the handle
 places the disks under compression, and a 125
 130

resilient cushion between the two parts of the plunger to hold the parts extended and to exert sufficient pressure upon the disk to eliminate air gaps when the disks are in normal condition.

In testimony that I claim the foregoing as

my own, I have hereto affixed my signature in the presence of two witnesses.

PAUL J. RAY.
